CARRIER CONTROLLED RADIO RECEIVER

R Lee Hollingsworth, Riverhead, N. Y., assignor to
 Radio Corporation of America, a corporation of
 Delaware

Application April 18, 1942, Serial No. 439,480

9 Claims. (Cl. 250—20)

My present invention relates to radio receiver control circuits, and more particularly to carrier-controlled receiver circuits.

One of the principal objects of my present invention is to provide a novel method of, and means for, controlling the output volume of a radio receiver; the method comprising the steps of rectifying received carrier energy, and utilizing the rectified carrier voltage to control the alternating current supply rectifier thereby to regulate the plate supply voltage as a function of carrier intensity.

Another important object of my invention is to provide in a receiver a means for compensating for carrier fading; for controlling the modulation level in the audio amplifier when the carrier fades; for inter-station muting and partial muting on deep selective fading; and for increasing the amplifier grid bias as the plate voltage is still further increased on carrier fading thereby guarding against distortion due to overloading.

Another object of my invention is to provide a system for securing automatic gain control and automatic frequency control in a radio receiver; the control actions being secured as a result of voltage changes on the grid and plates of the predemodulator stages as a function of carrier strength.

Still other objects are to improve generally the efficiency of automatic gain control circuits for receivers, and more especially to provide such circuits in a reliable, economical and readily-manufacturable manner.

The novel features which I believe to be characteristic of my invention are set forth with particularity in the appended claims; the invention itself, however, as to both its organization and method of operation will best be understood by reference to the following description taken in connection with the drawing in which I have indicated diagrammatically a circuit organization whereby my invention may be carried into effect.

Referring, now, to the accompanying drawing, let it be assumed that the receiver shown is generally of the short wave type employing a signal collector 1, which may be a dipole. Of course, the receiver may be of the usual broadcast type operating in the 550 to 1700 kilocycle (kc.) range. The receiver may receive carrier waves which are amplitude modulated by any desired signal intelligence, such as speech, music and the like. The radio frequency amplifier 2 is conventional; it may comprise the usual tunable input circuit 2'. The following stage 3 is a mixer, or first de-

tector; it is assumed the receiver is of the superheterodyne type. Such a mixer stage may employ a pentagrid converter tube of the 6A7 type. The tunable input circuit 3' is coupled to the output circuit of amplifier 2; the first, or signal input, grid is connected to input circuit 3'.

Local oscillations, of a frequency differing from the selected signal frequency by a predetermined intermediate frequency (I. F.), are produced at 10 3''. The oscillations thereof may be applied to the oscillator grid, as schematically represented, so as to produce the I. F. signal energy in the resonant primary circuit of I. F. transformer 4. The oscillator 3'' may include any desired type 15 of tube, such as a triode. In such a case, let it be assumed that the tunable oscillation circuit is connected between control grid and cathode, while the plate is connected by feedback coil 30 to plate voltage supply lead 20.

20 The plate supply lead 20 is additionally connected to the plates of each of amplifier 2 and mixer tube 3. Of course, one or more I. F. amplifiers may follow the I. F. transformer 4. The plates of such amplifiers would be fed from the 25 line 20. The demodulator, or second detector, consists of tube 5. The latter may be a triode whose anode and grounded cathode function as a diode rectifier. The anode of tube 5 is connected to the high side of the I. F.-tuned input 30 circuit 4'. The load resistor 6 develops the modulation signal voltage from the rectified I. F. current. The resistor 6 may be bypassed for I. F. currents. The slider 6' may derive any magnitude 35 of signal voltage from load 6. The switch arm 8' may be adjusted to position 7 to carry a portion of the voltage to a desirable telegraph termination, which is usually a tone keyer. If it is desired to feed the signal voltage to an audio amplifier (not shown), then switch arm 8' is 40 adjusted to position 8.

The unidirectional voltage across resistor 6 is proportional in magnitude to the carrier intensity. The carrier-derived unidirectional voltage is applied over line 19 to the input circuits of the amplifier 2 and mixer 3. The letters "AVC" indicate that the line is the automatic volume, or gain, control connection. Appropriate filter network 17—18 is inserted in the AVC connection, and provides a proper time delay action. Filter 45 resistors 19' may, also, be inserted in the connections to the signal grid circuits. The AVC connection may be made to the signal grids of the I. F. amplifiers, if the latter are used.

50 The power supply circuit comprises the supply transformer 12 whose primary winding is fed

with alternating current, say, at 60 cycles. The secondary has two sections. Power rectifiers 10 and 11 have the anodes thereof connected to opposite ends of secondary section 12'. The section 12" supplies heating current to the filaments of the rectifiers 10 and 11.

Each rectifier is provided with a control grid. Thus grid 10' is positioned between the plate and filament of tube 10, while grid 11' acts to control the electron stream in the rectifier 11. The midpoint of section 12' is connected through the series inductances of filter 13 to the negative end of the power supply potentiometer. The latter consists of resistor sections 14 and 15; the junction of the latter is grounded. The filter 13 comprises parallel condensers, and lead 15' connects the midpoint of section 12" to the positive end of potentiometer resistor 15. The lead 20 is connected to a desired voltage point on resistor 15 so as to energize the plates of tubes 2, 3 and 3' properly.

AVC bias is applied to the grids 10' and 11' of power rectifiers 10 and 11. This is done by connecting both control grids to any desired point on resistor 6; the lead 9 may be considered an extension of the AVC circuit. The path including resistor 16 connects the signal grids to a point on potentiometer section 14 which is at a proper negative potential. Resistors 16, 17 and condenser 18 provide a time delay circuit in the AVC connection. Switch 21 may connect the control grid of tube 5 to the AVC circuit, or to the plate of the demodulator. In the latter case, the tube 5 functions as a diode without AVC voltage applied to its grid.

Considering, now, the operation of the system, assume that no modulated carrier waves are being received. In that case the voltage across resistor 6 is zero, and the rectifier control grids 10' and 11' have minimum bias. Hence, the voltage across resistor 14, the signal grid biasing source, is a maximum. As a result, the negative bias on all grids is set at a predetermined value; and the gain of each stage is materially decreased. Concurrently, the drop across plate supply resistor 15 increases, and tends to increase the plate voltage of the controlled tubes. If switch 21 is thrown to contact 21', the grid of demodulator 5 is biased to secure muting action. When switch 21-21' is closed, the effect is to further isolate the radio frequency section from the audio section during no-signal state. When rectified carrier current passes through load resistor 6, the voltages across resistors 14 and 15 are reduced. At first the gain of the receiver is caused to rise by this reduction. When the signal voltage across resistor 6 is the dominant factor of control, the gain of the system is reduced.

When modulated carrier waves of sufficient intensity are received, the gain is linearized by the increasing bias developed across resistor 6. The rectifier grids 10' and 11' being biased negatively cause the plate voltages to the various plates to be reduced. Furthermore, the AVC bias applied over lead 19 to the signal grids aids in control over the gain of the system. The reduction of plate voltage and increase of AVC bias are such that the carrier amplitude at the input circuit 4' is substantially uniform over a wide range of carrier variation at signal collector 1. It is intended that the increase in plate voltage on fading should be enough over that of the grid voltage rise to increase the gain of the receiver. Hence, muting for quiet tuning between stations, and for controlling blasting during selective fading,

may be made even more positive by adding this negative control voltage to the grid of tube 5, or another tube that might be selected for this purpose.

Thus, a system has been shown for compensating for carrier fading; for controlling the volume (partially) of the modulation level in the audio amplifier when the carrier fades; for muting between stations and partial muting on deep selective fading; and for increasing the grid bias as the plate voltage is still further increased on carrier fading, thereby guarding against distortion due to overloading.

Another feature in this circuit is the inherent automatic frequency control (AFC) that is possible as a function of the carrier strength. Most oscillators are subject to variation in frequency as the plate voltage is raised or lowered. Therefore, in such a circuit as I have described, in which both the plate and grid voltages vary as a function of carrier strength, this element of control may be used to cause the local oscillator to center itself, or rather its resultant output, through the I. F. amplifier, just as the receiver linearizes its gain, but only in one tuning direction since this action reduces the capacity across the tuned oscillator circuit through the medium of the oscillator tube.

It is practical to employ AFC in a receiver even though it is effective only through a capacity change. Tuning to a lower frequency would require manual tuning slightly beyond the desired station frequency to set the oscillator and radio frequency in the automatic range. This over-swing of the tuning dial is usually a natural tendency. Tuning from a lower to a higher frequency would cause the AFC to tune the station in automatically as it is approached by manual tuning. That the radio frequency circuits tune, as a result of increased plate and grid AVC, is obvious. Therefore, the system of AVC as herein described, with its ability to swing the oscillator and radio frequency amplifier tuning to a certain extent, is practical due to the amount of AVC available to both the plate and grid circuits of the tubes controlled.

This method of AFC is most effective when receiving high frequency signals, as for instance frequency modulated carrier signals (FM) of comparatively narrow modulation band width, in that it compensates for frequency changes in the receiver due to temperature changes. Also, this method of AFC is most desirable when receiving high frequency signals of the amplitude variety within the primary or non-fading area; looking to the possibility of sky wave suppression for local broadcast usage of certain high frequency bands so that every small newspaper could afford a local station.

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

What I claim is:

1. A method of controlling the gain of a signal amplifier tube provided with at least a cathode, signal control electrode and a signal output electrode, which includes the steps of applying signals to the control electrode, rectifying low frequency alternating current to provide energizing voltage for at least said output electrode, rec-

tifying said signals to provide a control voltage, and automatically controlling said alternating current rectification with said control voltage thereby to vary the amplifier gain.

2. A method of controlling the gain of a signal amplifier tube provided with at least a cathode, signal control electrode and a signal output electrode, which includes the steps of applying signals to the control electrode, rectifying low frequency alternating current to provide energizing voltage for at least said output electrode, providing biasing voltage for said control electrode from the rectifier alternating current, rectifying said signals to provide a control voltage, and automatically controlling said alternating current rectification with said control voltage thereby to vary the amplifier gain.

3. A method of controlling the gain of a signal amplifier tube provided with at least a cathode, signal control electrode and a signal output electrode, which includes the steps of applying signals to the control electrode, rectifying low frequency alternating current to provide energizing voltage for at least said output electrode, rectifying said signals to provide a control voltage, and automatically controlling said alternating current rectification with said control voltage thereby to vary the amplifier gain, and concurrently controlling the voltage of said control electrode with said control voltage to augment the gain variation.

4. A method of controlling the gain of a signal amplifier tube provided with at least a cathode, signal control electrode and a signal output electrode, which includes the steps of applying signals to the control electrode, rectifying low frequency alternating current to provide energizing voltage for at least said output electrode, rectifying said signals to provide a control voltage, automatically controlling said alternating current rectification with said control voltage thereby to vary the amplifier gain, deriving demodulated signals from the signal rectification, and utilizing said rectified alternating current to develop control voltage for preventing said derivation of demodulated signals.

5. In a radio receiver provided with at least one modulated carrier wave transmission stage, said stage having a tube provided with at least a cathode, wave input electrode and a cold electrode; the method which includes translating alternating current into direct current for energizing the receiver, deriving from the direct current a positive potential, applying said positive potential to the cold electrode, rectifying received modulated carrier wave energy to provide a control voltage, and controlling with said control

voltage the efficiency of translation of said alternating current into direct current thereby to regulate the magnitude of said positive potential.

6. In a radio receiver provided with at least one modulated carrier wave transmission stage, said stage having a tube provided with at least a cathode, wave input electrode and a cold electrode; the method which includes rectifying an alternating current to provide a positive direct current potential for the cold electrode and a negative bias for the input electrode, rectifying received modulated carrier wave energy to provide a control voltage, and regulating in response to said control voltage said alternating current rectification thereby to regulate the input electrode bias value, and the magnitude of said positive potential.

7. In a superheterodyne receiver embodying a converter tube, a local oscillator tube and means for detecting the converted signal energy; the method including rectifying low frequency current to provide energizing direct current voltages for said converter and oscillator tubes, deriving from the detected signal energy a control voltage, varying said rectification to control the magnitude of said energizing voltages, and varying the energization of at least said oscillator tube with said variable-magnitude energizing direct current voltage in a sense to maintain the frequency of the converted signals substantially constant.

8. In a wave transmission system including at least one electronic device provided with at least an electron emission element, a cold output electrode and a cold control electrode; the method of regulating a characteristic of said device which includes the steps of providing energizing current for energizing the electrodes of said device, deriving voltages from said energizing current, applying to said electrodes said voltages derived from the energizing current, deriving a control voltage from transmitted waves, and regulating the magnitude of the energizing current with said control voltage thereby to vary the value of the applied voltages.

9. In an electronic system having a plurality of electron discharge devices and an energizing current supply network for providing energizing voltage for the respective electrodes of said devices; the improvement which comprises means for deriving a control voltage from electrical waves transmitted through the system, and means for regulating the magnitude of the energizing current flowing through the supply network in response to said control voltage thereby to vary said energizing voltage magnitude.
